United States Patent Office.

HERVEY B. DENNY, OF WASHINGTON, DISTRICT OF COLUMBIA.

Letters Patent No. 92,588, dated July 13, 1869.

IMPROVEMENT IN COPY-HOLDERS.

The Schedule referred to in these Letters Patent and making part of the same.

To all whom it may concern:

Be it known that I, HERVEY B. DENNY, of the city and county of Washington, and District of Columbia, have invented a new and useful Copy-Holder for Printers and Copyists; and I do hereby declare the following to be a sufficiently full, clear, and exact description to enable those skilled in the art to which it appertains, to make and use the same, reference being had to the accompanying drawings, which are made a part of this specification.

My invention consists of a holder proper, of novel construction, adapted to hold the copy in a superior manner, and adjust the same as desired, and also to support, when necessary, a background-sheet or cloth, mounted by means of a rod or arm projecting in a convenient position from a base adapted to be fastened, by a suitable clamp, to a convenient object, or weighted, so as to rest on a table, said rod or arm being further preferably hinged to the base-plate, so as to allow the position of the holder to be readily changed, as desired, without moving said base.

In the drawings—

Figure 1 represents a perspective view of my copy-holder, adapted to be applied to a printer's type-case, a portion of which is shown in red outline, and representing, in red outline and broken lines, respectively, a "copy" and a background-sheet, as supported by the holder;

Figure 2 is an end view of the base-plate or clamp; and

Figure 3, a transverse section of the holder proper, on an enlarged scale, as represented in fig. 1.

A B represent a pair of rollers, preferably of rubber, provided with a metallic shaft, as shown, mounted in a suitable frame or bracket, C, the former, A, in fixed bearings, and the latter, B, at one or both ends, in elongated slots c, and pressed against said roller A by means of one or more suitable springs, D, grasping the shafts of both, as shown, or otherwise suitably applied.

The rollers A B are made of suitable length to accommodate the maximum width of copy, which is introduced between them, as represented, in red outline, in figs. 1 and 3, and held by the pressure of the spring or springs D.

a b represent handles or thumb-heads, one or more of which are applied to the shafts of one or both of the rollers A B, by which to rotate them, to bring the part of the copy being used at a more convenient height, or to indicate, by the edge of the front roller, or otherwise, the line on which the compositor or copyist is at work.

E represents a wire, or bar, or equivalent device, stretched across the frame and below it, between the rollers A B, and immediately behind the vertical plane of the copy, when held between said rollers, as

represented in fig. 3, for the support of a sheet of paper or cloth, indicated in black dotted lines in figs. 1 and 3, to form a suitable background for copy written on transparent or semi-transparent paper, as tissue-paper, and which sheet may be attached to it in any suitable and convenient manner, and remain attached, or be removed when not required.

F represents a rod or arm, connected, at its upper or outer end, to the rear side of the frame C, at its centre, in any suitable manner, and at its lower or inner end, preferably, by means of a horizontal hinge, as shown, to a base-plate, G'; being further preferably curved or bent, so as to project upward and outward from its juncture with the base or fastening, as shown, the object of which is to support the holder at a convenient height, more or less near the person using it, as desired, and on either side of its fastening, as to bring it into convenient position for the compositor to use his capital or small-capital letters, and, in all its movements, to allow the holder to maintain the copy in a vertical position.

The sole of the base-plate G, as shown, is oblique, or inclined to the hinge of the rod or arm F, to adapt it for the angle of the type-case to which applied, a portion of which is represented in red outline in fig. 1, and in section in fig. 2.

It is provided, at a suitable point, with a clamp, H, of suitable construction; adapted to engage with a bar of the case, as represented in said figs. 1 and 2, to attach said base-plate thereto.

The clamp H preferably consists of a pair of jaws, perpendicular to the plane of the base, hinged together at a point intermediate to their ends, as represented at h, provided, on their opposing surfaces, at their lower end, with spurs h', or otherwise suitably adapted to engage, to the requisite extent, with the part to which applied, and pressed apart, at their upper end, by means of a suitable spring, h", to force the clamping-ends together.

By simply pressing together the upper ends of said jaws with the finger and thumb, the device may be released.

One of the jaws of the clamp may be formed in one part with the base-plate, as shown, or it may be otherwise attached thereto.

This form of clamp or fastening, besides its simplicity of construction and effectiveness, adapts the device to be readily applied and removed, when desired, in the shortest possible time, and is therefore especially desirable.

For ordinary copying, the device may be provided with a weighted base, and adapted to stand on a table.

Having thus described my invention, the following is what I claim as new therein, and desire to secure by Letters Patent:

1. I claim the holder, consisting of the frame C c, rollers A B, spring or springs D, and handle or handles $a' b'$, adapted to operate substantially as described, for the purpose specified.

2. I claim the wire or bar E, or its equivalent, arranged substantially as described, for the purpose set forth.

3. I claim the rod or arm F, connected to the holder in any desired manner, and to the base or fastening by a horizontal hinge, g, as represented and described, for the purpose stated.

4. I claim the clamp H, consisting of a pair of hinged jaws, provided, on their opposing faces, at their lower end, with spurs h', and pressed apart above their hinge by a spring h", in combination with the base-plate G, as and for the purposes specified.

HERVEY B. DENNY.

Witnesses:

OCTAVIUS KNIGHT,
W. B. DEMING.
